(57) **CLAIM**

The ornamental design for an exercise console, as shown and described.

DESCRIPTION

FIG. 1 is a perspective view of an exercise console of the present invention;

FIG. 2 is a first end view of the exercise console of FIG. 1; FIG. 3 is a second end view of the exercise console of FIG. 1;

FIG. 4 is a right side view of the exercise console of FIG. 1; FIG. 5 is a left side view of the exercise console of FIG. 1; FIG. 6 is a top view of the exercise console of FIG. 1; FIG. 7 is a bottom view of the exercise console of FIG. 1; and,

FIG. 8 is a top perspective view of the exercise console of FIG. 1.

The broken lines shown represent portions of the exercise console that form no part of the claimed design.
